**APPARATUS FOR IGNITING AND OPERATING
GASEOUS DISCHARGE DEVICES**
Elmer J. Huberty and Albert E. Feinberg, Chicago, Ill.,
assignors to Advance Transformer Co., Chicago, Ill.,
a corporation of Illinois
Filed May 6, 1959, Ser. No. 811,297
22 Claims. (Cl. 315—257)

This invention relates generally to apparatus for igniting and operating gaseous discharge devices, and more particularly is concerned with the construction of a transformer for use in a gaseous discharge device system and with the system itself, in which the source of electrical power for the system comprises an A.C. line subject to variation and fluctuation in line voltage, the invention being specifically directed to structure providing substantially constant wattage or current flow through the gaseous discharge devices.

The primary purpose for which the invention herein was made was for application to gaseous discharge devices providing visible light output for illuminating purposes, although the invention may be applied to other gaseous discharge devices. The gaseous discharge devices which provide visible light are of several types, important of which are cold and hot cathode fluorescent lamps and metallic vapor lamps utilizing the visible radiation from mercury or sodium vapor or the like for their light output.

All gaseous discharge devices have in common several characteristics which are unique. The gaseous discharge device is a negative resistance device in that when it is operating, that is, a current is flowing through the same, its resistance decreases with voltage so that unless in some way prevented from doing so, the current will increase at a rapid rate until the device becomes practically a short circuit and either destroys itself or the conductors and circuit elements with which it is connected. Gaseous discharge devices are therefore ballasted, that is, provided with impedance to flow of current which limits the current to some predetermined value established as rated for the device operating at maximum efficiency and for longest operative life.

Another characteristic of gaseous discharge devices is that all have a much higher igniting voltage than operating voltage. The discharge through the gaseous discharge device which gives rise to the radiation is an ionization of gas within the envelope of the device and this gas must be broken down before there is any flow of current, comprising the ionization current. Thus, a high open-circuit voltage must be applied to the device, this voltage being higher than the operating voltage, and in most modern discharge devices being substantially greater than the line voltage. Once the lamp has ignited, it is essential that the voltage applied to the lamp drop to its operating value.

A system for igniting and operating gaseous discharge devices is ideally constructed using a transformer which has high leakage reactance deliberately built into the transformer so that upon open-circuit when there is substantially no current flowing in the output portion of the transformer the leakage reactance has a minimum effect, and the voltage is high; but when the discharge device has ignited and current flows in the output circuit the leakage reactance effect is substantial and the voltage decreases.

Various structures have been devised for assisting in the ignition of the devices, for providing suitable voltages for different kinds of devices and the like. Included in these structures have been those of the constant current or constant wattage type, in which the gaseous discharge load is desired to be operated at a constant current ir-

2

respective of substantial variations in the line voltage. These have been especially intended for use with the cold cathode type of discharge device and with the metallic vapor devices, although advantageously they can be used as well with ordinary fluorescent lamps.

The fluorescent lamp which is most familiar is a glass tube having a small quantity of ionizable gas therein, usually argon together with a small quantity of mercury, at a relatively low pressure such as 2 to 3 mm. and the walls of which are coated with phosphors which fluoresce when subjected to the ultra-violet radiation from the gas. The cathodes of such lamps are usually of the hot type, that is, they are intended to be operated at high temperatures for the purpose of producing clouds of electrons, either initially or continually during the operation of the device. The principal current flow and the voltage across the lamp are for the most part substantially constant during the life of the lamp. Changes in line voltage have minimal effect either upon the light output or life of the lamp, within normal ranges. The incandescence of the cathode produces emission of electrons at relatively low voltages, with nominal voltage drop at the cathode. This drop for a lamp having an operating voltage of 195 volts may be at most 15 volts.

In the case of cold cathode lamps, the cathodes are substantially larger in size than those of the hot cathode lamps, and are not heated to incandescence. Instead, it is believed, the electrons providing flow of current are knocked out of the cathode by positive ion bombardment, and hence a much higher voltage is required for the operation of such lamps. The cathode drop in a cold cathode lamp is very substantial and sufficient part of the total voltage drop across the lamp to be considered important in any given circuit. For example, a typical cold cathode lamp operating at a total voltage of 420 volts will have a cathode drop of about 105 volts. Obviously the greater the cathode drop the less the voltage available for light-producing discharge, which is in effect a flow discharge instead of an arc discharge as in the case of the hot cathode lamps.

It has been found that the cathode drop increases with age. Thus, for this reason, and in addition for compensating for the variations in line voltage, it is essential for the operation of cold cathode lamps that the current be maintained at a substantially constant value.

Cold cathode lamps usually have phosphors on the interior surfaces of their envelopes to fluoresce when bombarded by the ultra-violet rays of the glow discharge of the mercury or other gases which are also contained within the envelopes at low pressures. As in the case of ordinary fluorescent lamps, cold cathode lamps may contain argon or other inert gas at a pressure of about 2 or 3 mm. with a droplet or two of mercury suitable for vaporizing once the discharge has started.

Metallic vapor lamps are of the hot cathode type and usually have a gas therein at substantial pressure, such as for example, several atmospheres, and depend upon the arc discharge itself for the production of light. A pool of the metal heated by passage of current may initiate the discharge. Such lamps provide great brilliance and operate at relatively high temperatures. Their envelopes and seals are subjected to unusual stresses and hence great care must be taken to assure that the rated current flows in the lamps. Too high a current increases the temperature of the lamp and its seals, and too low a current decreases the light output. Obviously, such lamps are best operated at constant current, so that their life is prolonged and efficiency maintained.

An additional reason for using circuits and structures such as those of the invention for metallic vapor lamps is that such lamps are usually installed in street and highway lighting systems in which the lamps are spaced sub-

stantial distances apart and the voltage drop in the feed lines is not readily maintained constant, but varies with many conditions.

There have been constant current or wattage devices which depend upon the saturation of an iron core to limit the voltage or current which is supplied to the load. The structures of the prior art have been built with the belief that in order to achieve the desired results it has been necessary to saturate both the primary and secondary core portions of the steel or large portions of the core. Such structures that used small total core cross-sections have not utilized a series condenser to assist in the saturation of the core under the secondary winding.

The invention herein is based upon the discovery that the regulation can be achieved in a circuit having a capacitive reactive character by saturating only a very small portion of the total core length of the central winding leg under the secondary winding, but providing sufficient axial length for the saturated portion so that there is no possibility of the core acting as though it had an ordinary wave-shape-correcting bridged gap therein. The general proportions will be described in the detailed specification hereinafter.

The advantages of saturating only a very small portion of the core and nevertheless achieving the desired regulation relate to the core loss attendant upon high flux densities. In previous devices, it has been found that where the central winding leg is of the same cross sectional area throughout that the core loss of the steel exceeds even the copper loss.

The invention contemplates the saturation of only a small portion of the central winding leg and hence the core loss of steel is considerably reduced because of the small portion that is actually saturated.

It is the primary object of the invention to provide a transformer and system for igniting and operating gaseous discharge devices in which the output of the transformer is connected into a capacitively reactive load, and in which the current flowing in the load will be substantially constant irrespective of variations in line voltage energizing the circuit and irrespective of variations in the load characteristics, the said transformer having less losses than prior structures.

A further object of the invention is to provide a structure of the character described in which the noise and fringing of stray and extraneous flux is kept to a minimum because of the manner in which saturation is obtained in only that section of the core which is completely confined within the secondary winding.

Other objects of the invention are concerned with the various phases of the invention which will be brought out hereinafter, and these and other advantages of the invention will become apparent to those skilled in this art as the detailed description of preferred embodiments proceeds, in connection with which there are attached illustrations, more or less diagrammatic in nature, but which are fully understood by the skilled artisan.

In the drawings,

FIG. 1 is a sectional view taken through a ballast for igniting and operating gaseous discharge devices constructed in accordance with the invention, the view being somewhat diagrammatic and illustrating the transformer of the invention in plan aspect with a fragmentary portion of the canister and potting compound of the ballast being also shown.

FIGS. 2 and 3 are electrical circuit diagrams of two circuits for gaseous discharge devices either of which is capable of being used with the ballast of FIG. 1, the circuits being characterized by the fact that each circuit ignites and operates two series pairs of discharge devices.

FIG. 4 is a fragmentary view somewhat similar to that of FIG. 1 but showing only the left hand end of a modified form of the invention.

FIG. 5 is a fragmentary view similar to that of FIG. 4

and showing the left hand end of a still further modified form of the invention.

FIG. 6 is an electrical circuit diagram of a single gaseous discharge device apparatus utilizing the invention.

FIG. 7 is a view similar to that of FIG. 1 but of a modified form of structure for use with the circuit of FIG. 6.

FIG. 8 is a diagram of the current wave in the secondary winding of a transformer of the construction of the invention.

The invention is characterized by providing an iron core having a central winding leg upon which the windings of the transformer are wound, and there being at least a primary winding and a secondary winding, coaxial with the central winding leg and separated from one another by a shunt, such as for example, a magnetic shunt having an air gap and thereby providing the desired leakage reactance above referred to. The outer framing portions of the iron core comprise parallel outer legs spaced from the central winding leg on opposite sides thereof and forming windows within which the windings are located, and the ends of the outer legs having end portions directed toward and abutting the ends of the central winding leg on opposite edges thereof.

The general configuration of the transformer is completely conventional, in that any of the well known structures including core type and shell type cores may be used. In the case of the conventional shell type transformer core, which is usually preferred, the width of the central winding leg is twice the width of either of the outer legs, and the end bridging portions have the same width (measured along the axial length of the central winding leg) as the transverse width of the outer legs. Because of the structure thus far described, all of the benefits of scrapless stamping of the laminations and economical production may be obtained. The width of the central winding leg is the same under the secondary as it is under the primary winding. The invention will be described in connection with shell type cores.

According to the invention, the portion of the central winding leg which is disposed completely on the interior of the secondary winding is reduced in cross sectional area in an amount which provides the localized saturation that has been found effective to provide satisfactory regulation of the apparatus when one or more gaseous discharge devices are connected in the output of the secondary winding in a capacitive circuit. This localized reduction in area has substantially the same effect as reducing the entire cross sectional area of the central winding leg—and as a matter of fact, it may be stated that the excellent results achieved with the invention herein have proven that the prior structures which actually reduced the entire winding leg were constructed upon the basis of an erroneous assumption that such total saturation was necessary and hence introduced unnecessarily large amounts of saturation and large losses in such cores.

The reduction in cross sectional area at a localized part of the central winding leg may take any of several different forms, the most effective of which were found to be a single rectangular center opening, a group of notches along opposite edges, and a group of slots in the center. The cross sectional area at such part of the central winding leg is completely within the secondary winding and is reduced about 25% to 50% of its original area. This comprises decrease in transverse dimension across the center winding leg by the removal of metal. As for the axial dimension, that is, length along the center winding leg, of said removed portion of the metal, it should be sufficient to prevent excessive bridging of the flux. The total axial length of the openings or gaps or notches found desirable and effective has been approximately one to one and one-half the total reduction in the transverse dimension. Dimensions may vary depending upon

the size and characteristics of the apparatus, but the above general rules have provided excellent results.

In connection with the choice of proper reduction dimensions, flux density is of importance. It was found that best results were obtained when saturation of the restricted flux-passing iron was in the vicinity of 18,000 to 20,000 gauss. Increasing the flux density substantially above 20,000 gauss produces a tendency for the reduced section to permit flux bridging the air space remaining at the reduced section, and in addition may saturate the entire core at a relatively low level which produces the same effect as a continuous air gap without the presence of steel. In the case of such latter-mentioned effect, there would be a linear change of flux with variations of load or primary voltage, which is the opposite to that which it is desired to achieve. In such cases, excessively lengthening the reduced area along the axis of the central winding leg will increase the amount of steel operating at high flux densities and thereby also defeat the purpose of the invention by excessively increasing the losses.

The dimensions of gaps of structures such as Berger Patent 2,461,957 transversely of the center winding leg or core element wherein located are normally substantially in excess of 50% of the width of the central winding leg, and considering the axial dimension along the length of the winding leg are substantially less than 25% of the transverse dimensional width of such gaps. These gaps act in the manner described above in connection with the phenomenon at high flux densities, namely—the flux may pass across these gaps readily and give linearity to the total flux path, for correction of wave shape. The ideal gap of this type has no bridging portions, the ends of the gaps being small as mechanically feasible so that there is saturation at relatively low primary voltages to give the effect of a complete air gap. The invention herein operates on a totally different principle, since the remaining portions of the reduced area sections must have the desired saturation to give the regulation needed for maintaining constant current in the load.

In FIG. 1 there is illustrated a ballast, designated generally by the reference character 10, which is designed for use with either of the circuits 20 or 30 shown in FIG. 2 or 3, respectively. The ballast includes an iron core transformer 22 which is disposed within a metal canister 24 being potted therein with suitable potting compound 26 along with other elements some of which are shown in the circuit diagrams of FIGS. 2 and 3. The transformer 22 in this case comprises a shell type core which may be designated generally 32 and is formed of a pair of outer legs 34 and 36 each having inwardly extending projections 38 and 40 juxtaposed relative to one another respectively and inwardly extending bridging end portions 42 and 44. There is a central winding leg 46 which is engaged between the two outer legs 34 and 36, extending the entire length thereof. The bridging end portions 42 and 44 abut against the opposite edges of the central winding leg 46 adjacent the ends thereof in the abutting joints 48 and 50 which may be considered efficient magnetic connections. Notches cut at 52 at the corners of the outer legs 34 and 36 seat clamping members generally shown at 54 for maintaining the entire transformer in assembly.

Without going into great detail, it should be pointed out that the side legs 34 and 36 and the central winding leg 46 are all formed of thin laminations of electrical sheet steel, such as silicon or cold rolled steel, all in the manner well known in this art.

The projections 38 and 40 are not long enough to abut the side edges of the central winding leg 46 and hence form non-magnetic gaps at 56 and 58 which may be permitted to remain as air gaps or may be filled with such gap-filling material as well known. The projections and their air gaps form the two magnetic shunts 60 and 62.

The projections 38 and 40, cooperating with the bridging ends 42 and 44 provide windows 64, 66 and 68 along the length of the core 32, there being conforming pairs of windows on opposite sides of the said winding leg 46. 5 Each pair of windows on opposite sides of the central winding leg has a winding disposed therein, these windings being, respectively, right to left, a secondary winding S_1 , a primary winding P , and a secondary winding S_2 . These windings are tubular in configuration and are all coaxial with the central winding leg 46, being spaced along the length thereof. The windings are suitably insulated in accordance with known techniques, and each completely encloses a different portion of the central winding leg.

Attention is now invited to the relative dimensions of 15 the structure of the core 32. The width (up and down) of the central winding leg 46 transversely of its axis (right and left) is designated by the character A ; the widths of each of the outer legs 34 and 36 are similar and this dimension is designated B ; the widths (transverse dimension) of each of the bridging portions 42 and 44 are the same and are designated C . The dimensional relationships of conventional core structures of this general type hold true here, namely, $B=C$ and $A=2B$.

The difference between this above described structure 25 and known structures lies in the construction of the core portions under the secondary windings S_1 and S_2 . Since both are substantially the same, only the structure under S_1 need be described. The central winding leg 46 beneath the secondary winding S_1 is designated 70 and as will be seen there is a series of notches 71, 72 and 73 cut along opposite edges of the central winding leg, each pair of opposite notches being transversely aligned, so that the reduction of the cross section area of the portion 30 70 at each pair of opposite notches is measured by twice the depth D of the notches. The reduced area is $A-2D$. In an actual example, the dimension A was 1.5 inches, and the notch depth D was .2 inch, so that the decrease or reduction was 26.7% leaving a reduced area which was 73.3% of its former area. The notch width E was .156 35 inch so that the total axial length of the notched portions was .47 inch, which is 1.17 times the reduction of .4 inch, or 31.3% of A .

The structure of FIG. 1 could be used in either one of 40 the circuits of FIGS. 2 and 3. In FIG. 2 the circuit 20 is a straight transformer arrangement. The primary winding P is connected by the leads 80 and 82 across a suitable A.C. line of proper voltage and frequency, such as for example a 120, 240 or 277 volt A.C. line at 60 cycles. One of the terminals of leads 80 and 82 may be connected to ground.

The core 32 has shunts 60 and 62 positioned between 45 the winding P and the respective secondary windings S_2 and S_1 to provide the necessary leakage reactance. Secondary S_1 is in series with condenser C_1 and the pair of gaseous discharge devices L_1 . Secondary S_2 is in series with condenser C_2 and a pair of gaseous discharge devices L_2 . Each of the secondaries has a reduced area portion in the core beneath and interior of itself, as diagrammatically indicated at 70.

Each of the circuits is independent both as to ignition 50 and operation, although energized from a common primary P . The ignition voltage for each pair of discharge devices is determined by the turns ratio between the primary winding and the respective secondaries as well as the coupling between the windings. When ignition has occurred, the voltages across the respective discharge devices drop to a value dependent upon the leakage reactance and the total impedance of the respective circuits. These circuits are predominately capacitive so that a leading current flows in the secondary windings, which assists in the establishment of the desired saturation in the localized areas 70 of the central winding leg because iron in the vicinity of leading flux saturates more readily than iron in the vicinity of other flux.

75 In the event that the voltage of the line should vary or

other changes occur in the circuit, the saturation of the core areas 70 will prevent changes in the current flowing in the respective circuits.

In FIG. 3, the primary winding of the circuit 30 is connected from the lead 84 between the pairs of discharge devices L_1 and L_2 and the lead 86 between the secondaries S_1 and S_2 so that it is in autotransformer relationship with each of the secondaries to provide added voltage for ignition and operation of the discharge devices. In all other respects the circuits function the same as those of FIG. 2.

In FIGS. 4 and 5 there are illustrated two variations of the physical construction of the transformer 22. In FIG. 4, the transformer 88 differs from the transformer 22 only in the respect that instead of the notches 71, 72 and 73 there are provided a series of relatively large slots 91, 92, 93 and 94 whose dimensions are as stated above, namely their decrease of the area of the central winding leg in the vicinity 70 under the secondary winding S_2 is from about 25% to about 50% and the total cumulative axial length of the gaps is from one to one and one-half times the total reduction, which in this instance comprises the transverse width F of the slots. F is equivalent of about 2D. The dimension between slots may vary and be controlled by the physical strength desired, the size of the apparatus and the like. All should be confined within the secondary winding S_2 .

In FIG. 5, the transformer 98 is the equivalent of those described in FIGS. 1 and 4, but is of the forced-core type. In this type of transformer, the outer legs 34, 36 and the bridging ends only 44 of which is shown comprise an integral closed, rectangular frame-like structure, and the windings are mounted on the central winding leg 46 which is thereafter forced into the center of the frame-like structure to abut the inside of the bridging ends as at 50. The core is usually held together by means of rivets such as at 109. Instead of either the notches of FIG. 1 or the slots of FIG. 4, the reduction in the central winding leg at the section 70 is achieved through the use of a rectangular single cutout 101 the dimensions of which again are as set forth above, namely the transverse dimension of the leg 46 is reduced from 25% to 50% of the width of the winding leg, and the axial dimension is from one to one and one-half times the reduction.

As noted from the above, the circuits and transformers described have been intended for use with circuits which include at least two pairs of gaseous discharge devices. This is not intended as a limitation since either more or less discharge devices may be used with a single transformer. In FIGS. 6 and 7 the same structure as that shown in FIG. 1 using one-half of the circuit of FIG. 3 is illustrated except for use with a single gaseous discharge device. Also, a single notch 171 has been substituted for all notches 71, 72 and 73. The ballast 110 has a transformer 122 which has only a primary winding P and a secondary winding S_1 serving a lamp L_1 in series with a condenser C_1 . The equivalent elements of the transformer 122 have the same characters of reference as those of FIG. 1 but with the prefix "1." The operation is the same as for either of the discharge device circuits of FIG. 3.

It has been found that the wave shape of the current in the secondary of a device constructed according to the invention is somewhat as shown in FIG. 8, with a wave having a dip. This not only provides good light output and long life for the gaseous discharge device, but is also self-compensating for changes in current by changes in the relative sizes of the major and minor peaks.

Another important benefit which is achieved through the use of the invention, and which is in addition to the principal purpose of the structure, is that the location of the saturated portion of the core in a portion of the central winding leg completely enclosed by the secondary winding prevents stray and fringing flux from passing into the canister 24 or 124 and thereby decreases the

buzzing and noise in said canisters and stray magnetic fields.

As an example of the structures of the invention, a ballast was constructed according to the circuit of FIG. 2 and with the notched arrangement of FIG. 1. The total length of the core was 7 inches; the width was 4 inches; the dimension A was 1½ inches; the dimension B was ¾ inch; the shunts 60 and 62 were .38 inch wide; the gaps 56 and 58 were .05 inch; the windows 64 and 68 were 1.624 inches; window 66 was 1.5 inches; dimension D was .2 inch; dimension E was .156 inch; the distance between the notches was .219 inch; the transverse dimensions of the windows was ½ inch each. The bridging ends, i.e., dimension C was slightly less than dimension B; the distance from the left hand edge of the notch 71 to the right hand end of the central winding leg 46 was 2 inches.

The stack height of the core 32 was 1 inch; each secondary had 4600 turns of No. 32 gauge wire; the primary winding P had 370 turns of No. 20 gauge wire.

This transformer was connected into a circuit in which the line voltage across the primary winding was 118 volts, 60 cycles; the secondaries were each connected to a pair of commercially available hairpin-shaped cold cathode fluorescent lamps 25 millimeters in diameter and 93 inches long, making a total of four lamps for the circuit. These lamps ignite at 750 volts, a series pair igniting at about 1350 volts; they operate at a voltage of 420 volts each, so that the drop across a pair is about 840 volts; they draw about 120 milliamperes and are rated at about 42 watts each. Each of the condensers C_1 and C_2 was a .21 microfarad condenser rated at 1600 volts.

The lamps ignited and operated satisfactorily for substantial variations in line voltage. The voltage across each secondary was 1550 volts, and across the condenser 1240 volts. The circuit power factor was .95. Flux density measurements showed a 18,500 gauss in the saturated areas and a density of 14,500 gauss in the unsaturated areas.

To demonstrate the regulation of the circuit, choosing as standard a line voltage of 118 volts, in varying the line voltage from about 99 volts to 125 volts, the total variation of lamp current was not more than 2 milliamperes, which is approximately 2% total, or 1% on either side of average.

The invention is applicable to other circuits in which other than cold cathode lamps are used, and to apparatus in which the transformer is not necessarily of the shell type having a central winding leg. The teachings of the invention provide constant wattage where required.

So-called core type transformers are often in the form of rectangular structures with the windings coaxial and disposed on different portions of one elongate leg, the other leg being disposed parallel to the winding leg and having no portions of the windings thereon. This structure as well as those structures in which the windings are divided in two and have half on each of the parallel legs, having the same amount of flux threading each leg instead of having the central winding leg carry twice the flux as in either of the outer legs of the structures illustrated herein. The invention is of course applicable to any of these structures and the provision of the localized saturated portion beneath the secondary winding carrying the leading current can produce the constant current apparatus desired. In the case of the structure with the half windings on the respective legs, the reduction of core will be provided under each half of the secondary winding, and in the case of the single secondary winding and unoccupied parallel leg, all of the reduction will be under the secondary winding.

In addition to variations in the structure of the transformer per se the circuits may be different from those illustrated. Also the form of the reductions may vary,

as for example, using round instead of rectangular configurations.

Some expression has been made of the theories under which it is believed certain phenomena occur, but these are only intended to assist in an understanding of the explanation. Notwithstanding that such theories may be incorrect, the structure which is described hereinabove and claimed hereinafter produce the desired functions, irrespective of the basis for the operation thereof. No limitations are to be inferred from the statements of such theories, or the absence of others.

What it is desired to secure by Letters Patent of the United States is:

1. Apparatus for igniting and operating gaseous discharge means from a source of A.C. voltage which comprises an iron core transformer including an elongate flux conductive element, a primary winding and a secondary winding each coaxially mounted on a different portion of said element and coupled relative one another to provide leakage reactance in the secondary winding during operation of said apparatus, said primary winding adapted to be connected to said source, a capacitive load circuit including gaseous discharge means connected with said secondary winding to have the current of said secondary winding flowing therein of leading character, the said element being of substantially uniform cross sectional configuration along the length thereof, and means for providing substantially constant current flow in said load circuit comprising a reduction of area of said portion of said element upon which said secondary winding is mounted of dimensions to provide a localized saturated portion of non-linear permeability confined between the ends of said secondary winding.

2. Apparatus as claimed in claim 1 in which the reduction transversely of the element is at least approximately one quarter of the whole, and in which the axial dimension of the reduction is at least one quarter the width of said element.

3. Apparatus as claimed in claim 1 in which the flux density of the localized saturated portion during operation of said gaseous discharge means is between 18,000 gauss and 20,000 gauss.

4. Apparatus as claimed in claim 1 in which the reduction transversely of the element is from 25% and 50% of the whole, and the dimension of the reduction along the length of the element is from one to one and a half times the transverse reduction.

5. Apparatus as claimed in claim 4 in which the flux density of said localized saturated portion is from 18,000 gauss to 20,000 gauss during operation of the gaseous discharge means.

6. Apparatus as claimed in claim 4 in which said reduction comprises at least a pair of transversely aligned notches on opposite edges of the said element.

7. Apparatus as claimed in claim 4 in which said reduction comprises a series of cut-outs in said element.

8. Apparatus as claimed in claim 7 in which said cut-outs are notches on the edges of said element.

9. Apparatus as claimed in claim 7 in which said cut-outs are bridged slots in said element.

10. Apparatus as claimed in claim 4 in which said reduction comprises a single opening in the center of said element.

11. Apparatus for providing substantially constant wattage in a circuit for igniting and operating gaseous discharge means, which comprises an iron core transformer having a primary winding and a secondary winding, said transformer having an elongate primary flux path member of uniform cross section thereon along its length and the windings mounted thereon coaxially therewith and spaced from one another to provide leakage reactance between them, said primary winding adapted to be connected across a source of A.C. voltage, means adapted for connecting said secondary winding in circuit with said gaseous discharge means in-

cluding a capacitive reactor whereby to provide a capacitive circuit with said secondary winding, and a localized reduced area section in said flux path member on the interior of said secondary winding to provide a saturated flux path in a portion of said flux path member substantially less in length than the axial length of said secondary winding.

12. Apparatus as claimed in claim 11 in which the saturated flux path is less than 75% in area of the flux path member and has a length such as to provide non-linear flux permeability in the said flux path member.

13. Apparatus as claimed in claim 12 in which the length of the saturated flux path is one to one and a half times the reduction of the area thereof.

14. Apparatus as claimed in claim 11 in which the said primary and secondary windings are connected in autotransformer relation.

15. Apparatus for applying the ignition and operating voltage to a gaseous discharge device from a source of A.C. voltage at substantially constant current irrespective of variations in the circuit, comprising a gaseous discharge device, a transformer having an iron core including a primary flux path leg, a primary winding connected to said source and mounted coaxial with said leg, a secondary winding connected to said discharge device and mounted coaxial with said leg, a shunt between said windings, a condenser in circuit with said secondary winding and discharge device whereby the operating current in said secondary winding is predominantly capacitive, said leg having substantially uniform cross sectional configuration along its length beneath both windings, that portion beneath said secondary winding having a localized saturated section substantially less in length

30 than the length of said secondary winding and providing non-linear permeability to passage of flux through said portion for normal operating conditions of said apparatus.

16. Apparatus as claimed in claim 15 in which said saturated section comprises an area of reduced dimensions both transversely and axially of said leg.

17. Apparatus as claimed in claim 15 in which said saturated section comprises an area of reduced dimensions both transversely and axially of said leg with the transverse reduction being greater than 25% and the axial reduction being one to one and one-half times the transverse reduction.

18. Apparatus for supplying the ignition and operating voltages to a plurality of gaseous discharge devices from a source of A.C. voltage with substantially constant current flow in each of said gaseous discharge devices over a wide range of variation of circuit characteristics during operation, comprising at least two gaseous discharge devices, an iron core transformer having a primary winding and two secondary windings, each secondary winding being connected in a circuit with one of said gaseous discharge devices and having a capacitive reactor therein whereby to provide a leading current flow through said secondary winding during operation of said gaseous discharge device, a primary flux

50 conducting leg formed on said transformer and having uniform shape throughout its length, the primary winding being mounted on said leg in the center between the ends thereof and each of said secondaries being mounted on said leg on opposite sides of said primary winding and there being a gapped shunt between each secondary winding and said primary to provide leakage reactance during operation of said discharge devices, said leg having restricted sections one confined within each secondary providing localized saturation during operation and non-linear flux permeability.

60 19. Apparatus as claimed in claim 18 in which said restricted sections are each formed by reduction of area of said leg both transversely of said leg and along its length.

20. Apparatus as claimed in claim 18 in which said secondaries are both connected in auto-transformer relations with said primary.

21. Apparatus as claimed in claim 18 in which said restricted sections have a flux density during operation of the order of 18,000 gauss to 20,000 gauss.

22. In apparatus for igniting and operating gaseous discharge means wherein said apparatus includes: a source of A.C. voltage, an iron core transformer having a flux conductive element, primary and secondary windings each coaxially mounted on a different portion of said element and said windings being closely coupled one with the other to provide leakage reactance during the operation of said apparatus, said primary winding being adapted to be connected to the said source, and a capacitive load circuit including said gaseous discharge means connected to said secondary winding to have the current of said winding flowing therein of a leading character; the improvement

consisting of means for providing substantially constant current flow in said load circuit, said means comprising: a reduction of cross-sectional area in said flux conductive element in the portion of said element upon which said secondary winding is mounted, said reduced area being of a dimension to provide a localized saturated portion of non-linear permeability entirely confined between the ends of said secondary winding.
